UNITED STATES PATENT OFFICE

LEO O. GRANGE, OF CHICAGO, ILLINOIS, ASSIGNOR TO WALTER J. JARRATT, OF CHICAGO,
ILLINOIS

VULCANIZING APPARATUS

Application filed October 29, 1929. Serial No. 403,242.

My invention relates to an improvement in tire vulcanizing means and has for one purpose to provide improved control means for maintaining an even temperature of the tire or casing engaging surface. Another object is the provision of control means for use with a tire treating device in which a liquid or a gas or steam is employed, which control means shall be responsive to and shall control the temperature of the surface opposed to the tire, rather than the temperature or the pressure of the fluid heating medium. Other objects will appear from time to time in the course of the specification and claims.

I illustrate my invention more or less diagrammatically in the accompanying drawings, wherein—

Figure 1 is a side elevation;

Figure 2 is a section on the line 2—2 of Figure 1;

Figure 3 is a similar section through a variant form of device; and

Figure 4 is a similar section through a further variation.

Like parts are indicated by like symbols throughout the specification and drawings.

Referring to the drawings, A generally indicates any suitable outer shell or housing, with a bottom A¹ and an inner shell A². The space between the two shells, as at A³, may be filled with any suitable fluid heating medium. My device is adapted for example for use with steam type vulcanizers, or with vulcanizers in which an oil is employed as a heating medium.

B generally indicates any suitable heating means, herein shown as a resistance element applied to the lower face A¹ of the shell A. It will be understood that the member B is in circuit with any suitable source of electric energy which may reach it through the conductors B¹ B².

C diagrammatically indicates any suitable control means or make and break switch adapted to close or open the circuit through

the conductors B¹ and B² and the resistance element B. I may employ any suitable thermostatic element diagrammatically indicated as C¹ for actuating the member C, it being understood that when a predetermined temperature of the device is reached the member C¹ serves to break the actuating circuit and to cut out or disconnect the resistance element B. Since the details of the thermostatic element or the control do not of themselves form part of the present invention, and since controls of this type are familiar to the art, I do not indicate or describe the thermostatic element or control in detail but I find it convenient to employ a thermostatic element including a tube, such as C¹, which may easily be inserted into operative position and which may easily be withdrawn when desired.

As a means for applying the tube C¹ or for positioning it in actuating position I may employ a boss or projection generally indicated as D formed in or associated with the inner shell A² and provided with a bore D¹ one surface of which, as at D¹⁰, approaches close to the inner face of the shell A². The member D may be associated only with the inner shell A², as shown in Figure 4, or it may extend to and connect with the outer shell A, as shown in Figures 2 and 3. If the intermediate connecting portion D² is dispensed with it will be understood that the aperture D³ in the outer shell is aligned with the bore D¹.

In order to cause the member C¹ to respond to the temperature of the shell it may be desirable to recess the portion D², as shown in Figure 2 at D⁵, to permit the portion C¹ to respond only to the temperature of the inner shell and not to receive heat from the outer shell A or the intermediate connector D².

It may be desirable to protect the member C¹ from access of the fluid heating means, as shown in Figure 2. However, under some

circumstances and with some heating mediums the access of the medium to the member C¹ may be harmless or even may for some reason be desired. In the form of

5 Figure 3 the vent D⁶ is provided whereby the fluid containing interior of the housing between the two shells is connected to the bore D¹. When the thermostat member is removed free passage of the liquid is provided 10 and if desired the internal cavity may be drained in this fashion.

I illustrate different methods of connecting or mounting the thermostatic element in Figures 2 and 3 but I wish it to be understood that either form of connection may be used with either form of vulcanizer. Thus 15 I show in Figure 2 a slip connection including the exterior bosses E E¹ formed in the exterior of the shell A and provided with opposed parallel plane sides E². The stem or connecting members E³ of the member C conforms to the sides E², rotation of the member C being thus prevented. Any suitable locking means, such as the set screw E⁴, may 20 be employed for preventing longitudinal movement of the members C C¹.

In the form of Figures 3 and 4 I illustrate a screw threaded connection as at E⁵, between the members C¹ and E³ and the shell A but it 25 will be understood that the screwthreaded connection may also be employed with the form of Figure 2.

In the use of the device I may employ any suitable matrix G which conforms on its outer 30 face to the shell A² and on its inner face to the tire to be treated. The tire may be held in position for example by the blocks G¹, the clamp yoke G² with its securing screws G³ and the pressure applying screw G⁴.

40 It will be realized that whereas I have described and shown a practical and operative device, nevertheless many changes might be made in the size, shape, number and disposition of parts without departing from the spirit of my invention. I therefore wish my drawings and description to be taken as in a broad sense illustrative and diagrammatic rather than as limiting me to my specific showing. In particular I wish it to be understood that I do not wish to be limited to any specific heating means, a resistance element disposed as herein shown being illustrated merely as an example of a practical means for heating fluid. For example, gas heating 45 means might be employed. Whereas I have illustrated an electrical heating means and a temperature responsive control for its actuating circuit, it will be realized that my invention covers the obtaining of my desired effect, from avoidance of lag or delay, whether electric heating means are used or some other heating means and whether the control is through a make and break device in an electric circuit or through control of other and 55 non-electric heating means.

As to the actual heat responsive means employed I may for example employ a Bourdon tube and the drawings contain a diagrammatic showing of such a tube.

The use and operation of my invention are 70 as follows:

In previous vulcanizing and retreading devices for operating upon tires or casings it has been customary to employ thermostatic elements responsive to a fluid heating 75 medium, or pressure members responsive to pressure of an expansible fluid heating medium. One advantage of my invention is the employment, as the controlling or governing temperature, of the temperature of the member which actually engages the treated surface of the tire. It is the temperature of the area or surface of application of heat to the casing which is important, since it is this temperature which actually operates on the tire. In order to cause the control to respond to and to govern this temperature I insert a thermostatic element in an aperture in the shell which is separated only by a very thin 80 layer of metal from the actual tire engaging 85 surface. The thermostatically responsive element therefore accurately governs the actual temperature to which the tire is subjected with a range of variation too small to have any appreciably bad effect on the treatment. An important reason for governing the 90 temperature on the basis of the actual temperature treatment of the tire is to cut down or avoid the lag caused by the cooling of the shell by the application of cool rubber to it. Assuming that the shell is already heated to 95 vulcanizing temperature, and that a new casing is dropped into place it immediately absorbs heat from the shell and reduces the 100 heat of the shell. If the thermostatic element 105 responds to the pressure of the heating fluid, or to the heat of the fluid, then the shell, cooled by the contact of the tire, may be quickly cooled to a temperature too low to cure the rubber, although the liquid itself 110 may be at a proper temperature or pressure. The temperature loss caused by the insertion 115 of a new tire is not immediately reflected by a drop in temperature of the liquid or by a drop in pressure of the liquid and there is a 120 definite and considerable lag before the cooling effect upon the casing acts to reduce the 125 temperature or pressure and to cause the thermostatic element to cut in the actuating 130 circuit. After the lag, and when the circuit 135 is closed, there is still an additional lag until the liquid has again been heated to the desired 140 temperature, and until this excess of heat of the liquid has raised the temperature 145 of the shell to the desired minimum. This 150 double lag in practice may result in a circuit being cut in and cut out several times, after a cold tire is put in, before the curing temperature is reestablished.

155 Preferably the thickness of the metal of the

boss D and of the shell adjacent the thermostatic element are so controlled or proportioned as to limit or reduce the sensitivity of the control to temperatures in the boss and shell except those adjacent the effective inner face of the shell. As an example of such control I instance the spacing D² where, by increasing the bore, I insulate the member C¹ to a certain extent from response to temperatures remote from the inner shell.

While I do not wish to be limited to a round hole or to a cylindrical cavity, a cylindrical cavity with a tubular thermostatic element is a convenient control means. It will be understood that I do not wish to be limited to the particular form of boss and cavity shown, and that broadly my invention includes any means for causing the thermostatic element to respond closely to the heat of the inner shell and in particular to the heat of the inner surface of the inner shell. The forms of boss shown are practical means for spacing or positioning the thermostatic element for this purpose.

Referring to the matrix G, I may employ aluminum or any suitable material or alloy which readily transmits heat, in such fashion that the matrix members so rapidly pass on the heat received from the inner surface of the shell that their intervening space does not to any damaging extent interfere with the responsiveness of the thermostatic control to the temperature conditions at a point or zone of actual working contact with the tire.

While I do not wish to be limited to any particular resistance heating element, I find it useful and practical to employ a heating element in which generally flat resistance wires are compressed between plates of thin insulating material, such as mica.

I claim:

1. In a vulcanizing device, a vulcanizing shell adapted to be opposed to the article to be vulcanized, a housing associated with said shell, the space between shell and housing being adapted to be filled with a fluid heating medium, means for heating said fluid heating medium, and heat responsive means for controlling said fluid heating means, said heat responsive means including a portion positioned adjacent the inner face of said shell and extending through said housing and into the wall of said shell.

2. In a vulcanizing device, a vulcanizing shell adapted to be opposed to the article to be vulcanized, a housing associated with said shell, the space between shell and housing being adapted to be filled with a fluid heating medium, means for heating said fluid heating medium, heat responsive means for controlling said fluid heating means, said heat responsive means including a portion positioned adjacent the inner face of said shell and extending through said housing, and means being provided for aligning or posi-

tioning said heat responsive means with a portion adjacent the inner face of said shell.

3. In a vulcanizing device, a vulcanizing shell adapted to be opposed to the article to be vulcanized, a housing associated with said shell, the space between shell and housing being adapted to be filled with a fluid heating medium, means for heating said fluid heating medium, heat responsive means for controlling said fluid heating means, said heat responsive means including a portion positioned adjacent the inner face of said shell, and a boss or connection extending between and associated with the housing and shell, said connection being apertured to receive said heat responsive means.

4. In a vulcanizing device, a vulcanizing shell adapted to be opposed to the article to be vulcanized, a housing associated with said shell, the space between shell and housing being adapted to be filled with a fluid heating medium, means for heating said fluid heating medium, heat responsive means for controlling said fluid heating means, said heat responsive means including a portion positioned adjacent the inner face of said shell, and a boss or connection extending between and associated with the housing and shell, said connection being apertured to receive the heat responsive means, the portion of the aperture within the boss being of greater diameter than the portion of the aperture in or aligned with the shell, the heat responsive means being out of contact with the walls of that portion of the aperture having the increased diameter.

5. In a vulcanizing device, a vulcanizing shell adapted to be opposed to the article to be vulcanized, a housing associated with said shell, the space between shell and housing being adapted to be filled with a fluid heating medium, means for heating said fluid heating medium, and heat responsive means for controlling said fluid heating means, said heat responsive means including a portion positioned adjacent the inner face of said shell and extending through the wall of said housing, exterior securing means being provided therefor upon the housing wall, said securing means including a plurality of opposed lugs and a set screw associated with one of them.

6. In a vulcanizing device, a housing adapted to be filled with a fluid, electric means for heating said fluid, a circuit for said heating means, and a thermostatic control means in said circuit, adapted to make and break said circuit in response to fluctuations in temperature, a shell, forming part of said housing, adapted to be opposed to the article to be vulcanized, said thermostatic control means being positioned to penetrate said shell to a point closely adjacent the work engaging surface of the said shell, the electric heating means being substantially

more remote from said shell, the surface of said shell within said housing being provided with an enlarged portion adapted to receive said thermostatic control means, said enlarged portion being in communication with the exterior wall of said housing at a point remote from said shell.

Signed at Chicago, county of Cook and State of Illinois, this 25th day of October
1929.
